UNITED STATES PATENT OFFICE.

WILLIS H. WEISSBROD, OF GREENFIELD, MASSACHUSETTS.

KEY CASE.

Application filed January 18, 1927. Serial No. 161,740.

My invention relates to improvements in containers or cases for receiving and holding keys and the like, and consists essentially of a strip of flexible material, such as leather, 5 folded or made to be folded so that the end portions of said strip overlap the central or intermediate portion, thereby forming an enclosing member or element, a perforated re-enforcing sheet attached to said intermediate 10 portion to stiffen the same and serve as a direct support for other parts and members, and preferably forming with said intermediate portion a pocket which opens at one longitudinal edge, a plurality of key-holding or 15 supporting elements consisting in part of or including closed rings receivable in the perforations in said sheet, and a thong of peculiar construction passed through said rings, behind said sheet, and fastened to the latter, 20 together with such other parts and members as may be necessary or desirable in order to render the case complete and serviceable in every respect, all as hereinafter set forth.

The primary object of my invention is to 25 produce a case, of the class described, that is simple and comparatively inexpensive in construction, yet convenient, durable, flexible, reliable, and withal highly practical and efficient.

Another object is to afford means for easily, 30 quickly, and cheaply attaching the key-holding members to the case proper and fastening said members thereto or securing them in place therein.

A further object is to provide the case with 35 an easily accessible and fairly capacious pocket.

Other objects and advantages will appear 40 in the course of the following description.

I attain the objects and secure the advantages of my invention by the means illustrated in the accompanying drawings, in which—

Figure 1 is a front elevation of a key case 45 which embodies a practical form of my invention, the flaps being open; Fig. 2, a rear elevation of the reenforcing sheet with the rings attached thereto by the thong and before the ends of the latter are cut off, and, 50 Fig. 3, an enlarged sectional detail of certain of the new structural features.

Similar reference characters designate similar parts throughout the several views.

In the first view one of the swivel snap 55 hooks is omitted to disclose the peculiar perforation provided in the reenforcing sheet to

receive the ring by means of which the eye of each hook is supported from and in the case. In this view, also, a portion of the re-enforcing sheet is broken out in order more 60 clearly to emphasize the fact that there is a pocket between the intermediate portion or back of the strip forming the case proper and said sheet.

This key case comprises a strip of flexible 65 material divided by two vertical creases or bending portions, indicated at 1—1, into a back 2 and flaps 3 and 4, the two latter being respectively provided with male and female parts 5 and 6 of a glove fastener; a reenforcing sheet 7 attached to said back, preferably in such a manner as to form with said back 70 a pocket indicated by the arrow in Fig. 1; a plurality of rings 8 from which depend 75 swivel snap hooks 9, there being six of said rings in the present example, but there may be more or less than that number; and a thong 10 by means of which said rings are held in place in said sheet.

The flap 3 is adapted to be folded over onto 80 the front of the sheet 7 and the rings 8 and hooks 9, and over the keys carried by said hooks, and the flap 4 is adapted to be folded over onto the outside of said first-named flap, when the female member 6 is snapped 85 into engagement with the male member 5, thus enclosing the contents of the case and securing the flaps in closed position. Upon disengaging the fastening members and opening the flaps access is had to the contents of 90 the case. Structurally and functionally 95 these folding parts and their fastening members are not unlike corresponding parts and fasteners in other key cases, and may be varied to a considerable extent.

The reenforcing sheet 7 is a stiffening strip 100 of flexible material, such as is commonly used in key-case construction, and is placed against the inner face of the back 2 and secured to said back by lines of stitching, of which further mention will be made hereinafter. One vertical edge of the sheet 7, throughout the greater portion of its length, is left unsecured to the back 2 to provide an entrance to the space between said back and sheet, and thus make of said space a pocket that is accessible from the outside. Preferably it is the right-hand edge of the sheet 7 that is left free to provide the entrance to the pocket.

The hooks 9 are of the ordinary snap and 110 swivel type, and each has at the upper end an eye 11 with which is engaged one of the rings

8. The present construction enables the rings 8 to be attached to the sheet 7 after said rings have been attached to the eyes 11, which is an advantage because the hook units can be made up complete initially, and then with the utmost facility mounted in place as elements of the case. To this end the sheet 7 has sets of upper and under holes 12 connected by slits 13 punched therein, and the tongue 10 is provided.

This case being designed to include six hooks 9, there must be a corresponding number or sets of holes 12 and slits 13. These are located side by side in the sheet 7 near the upper edge thereof, and in each set are two holes 12, one above the other, and a vertical connecting slit 13, as clearly shown in Fig. 1. Each ring 8, with the eye 11 of one of the hooks 9 attached thereto, is pushed through one of the slits 13 until a portion of said ring is behind the sheet 7, and portions of said ring are in the holes 12 at the top and bottom of said slit. After the ring has been pushed through the slit the edges of said slit come together again inside of the ring. The rings 8 are placed in position and secured by the thong 10 before the sheet 7 is stitched to the back 2. The thong 10 is made of flexible material that can be stitched, and initially said thong is longer than the sheet 7 is wide. The intermediate portion of the thong 10 is of a length and width that enables it to be located in those portions, of all of the rings 8, which are behind the sheet 7, while the end portions of said thong are wider or project beyond both longitudinal edges of said intermediate portion, such wide parts being respectively designated by the numerals 14 and 15. Thus there is a head at each end of the thong. Preferably one of these heads, as 15, has the shape of an arrow head.

After the rings have been inserted in the perforations in the sheet 7, the thong 10, with the head 15 leading, is thrust through said rings behind said sheet, until the narrow intermediate portion of the thong is located in all of the rings. Next both heads 14 and 15 are stitched, as represented at 16, to the sheet 7 adjacent to the longitudinal edges thereof. And finally the portions of the heads 14 and 15 that project beyond the reenforcing sheet are cut off.

The sheet 7 is now stitched to the back 2, there being two lines of stitching 17 adjacent to the top and bottom of said sheet, and a line of stitching 18 adjacent to the longitudinal or vertical edge of the sheet which edge is opposite to that where entrance to the pocket is had, also an additional line of stitching 17 below the thong 10, and a short vertical line of stitching 19 adjacent to the edge of the sheet that forms the pocket entrance. This entrance is below the second line of stitching 17 from the top. The thong 10 is thus very firmly and securely fastened in place at the

ends, the lines of stitching 16 fastening the heads 14 and 15 to the sheet 7, and the lines of stitching 18 and 19 fastening said heads again to said sheet and also to the back 2 and in turn said thong prevents the rings 8 from being drawn outwardly through the slits 16. The rear or inner portion of the rings 8 and the portion of the thong 10 that is in direct engagement therewith are loose or free in the space between the back 2 and the sheet 7, between the lines of stitching above and below and at the ends of said space, and said thong does not hold said rings absolutely rigid, hence the rings have a certain amount of lateral play or swinging movement.

Inasmuch as the part of the thong 10 that directly engages the rings 8 must be comparatively narrow, the same would not be wide enough to stitch to the sheet 7 and to the back 2, or, in any event, to stitch thereto to the extent required for security, without providing heads to receive the stitching, and heads of sufficient width to afford when stitched in place the necessary areas of directly and intimately attached surfaces and parts. If it were possible to take only a few stitches in the thong at each terminal, they would be liable quickly to pull out, when said thong sooner or later would be pulled out through one of the perforations in the reenforcing sheet, and the usefulness of the key case would be at an end.

By initially providing the thong 10 at one end with a pointed or arrow-head-shaped head, and using this head with which to thread the thong through the rings 8, such threading operation is greatly facilitated and expedited, even though it is necessary at this time to fold said head longitudinally to some extent while pushing it through said rings.

Keys are engaged with the hooks 9 in a similar manner as keys are engaged with the hooks of other cases, and this key case as a whole is used in practically the same way as are others.

Each hook 9 is swiveled to its eye 11 and therefore free to rotate, said eye is loosely held by the ring 8 above, and said ring has a certain amount of lateral movement as hereinbefore explained, consequently a key attached to said hook is capable of being turned about in almost any direction without being impeded by the case, which is an important factor in a device of this character.

More or less change in the shape, size, construction, and arrangement of some or all of the parts of this key case, in addition to those hereinbefore specifically pointed out, may be made, without departing from the spirit of my invention or exceeding the scope of what is claimed.

What I claim as my invention, and desire to secure by Letters Patent, is—

1. In a key case, a back, a perforated re-

enforcing sheet attached to said back, rings in the perforations in said sheet and projecting behind the same, a straight flexible thong passing through said rings behind said sheet, 5 said thong having an intermediate portion with parallel edges, which is the portion that passes through the rings, and end portions beyond said rings that are wider than said intermediate portion, and said thong being 10 of uniform thickness to render the same equally flexible throughout, and securing means for said end portions.

2. A key case comprising a back, a perforated reenforcing sheet attached to said back, 15 rings receivable in the perforations in said sheet, a straight thong receivable in the portions of said rings that are behind said sheet, said thong being longer than the width of said sheet to facilitate fastening it thereto, 20 and having end portions wider than the intermediate portion of said thong to afford sufficient fastening areas, with one such end portion arrow-head shaped to facilitate threading the thong through the rings, and 25 means to secure said end portions to the sheet, the parts of the end portions that project beyond the sheet being cut off after the fastening operation.

3. A key case comprising a back, a perforated reenforcing sheet attached to said back, 30 rings receivable in the perforations in said sheet, a straight thong passing through said rings behind said sheet, said thong having an intermediate portion with parallel edges 35 which is the portion that passes through the rings, and end portions beyond said rings that are wider than said intermediate por-

tion, with one such end portion arrow-head shaped to facilitate threading the thong through the rings, and said thong being 40 longer than the width of said sheet, and securing means for said end portions, any part of said thong that projects beyond the sheet being cut off after the thong is fastened to the sheet. 45

4. In a key case, a back, a reenforcing sheet attached to said back, said sheet having therein sets of holes connected by slits, said holes in each pair having continuous edges except where they open into the connecting 50 slit, rings adapted to be forced through said slits and to be received in said holes, a retaining member passing through said rings behind said sheet, and means to secure said retaining member in place. 55

5. A key case comprising a back, a perforated reenforcing sheet adapted to be stitched to said back, rings receivable in the perforations in said sheet, and a thong receivable in the portions of said rings that are behind said sheet, when the rings are in place, said thong being longer than the width of said sheet, and having end portions wider than the intermediate portion of said thong, 60 with one such end portion arrow-head shaped to facilitate threading the thong through the rings, and said end portions being adapted to be fastened to said sheet by stitches passing through the end portions as 65 well as through the sheet, and then to have the parts thereof that project beyond the sheet cut off. 70
